UNITED STATES PATENT OFFICE

ROBERT H. YOUNG, OF PORTLAND, OREGON

DESIGN FOR A SAUSAGE COOKER

Application filed April 11, 1933. Serial No. 47,758. Term of patent 3½ years.

To all whom it may concern:

Be it known that I, ROBERT H. YOUNG, a citizen of the United States, residing at Portland, in the county of Multnomah and State of Oregon, have invented a new, original, and ornamental Design for Sausage Cookers, of which the following is a specification, reference being had to the accompanying drawing, forming part thereof.

I claim:

The ornamental design for a sausage cooker, substantially as shown.

ROBERT H. YOUNG,
